(57) **CLAIM**

The ornamental design for a current transducer, as shown and described.

DESCRIPTION

The patent or application file contains at least one drawing executed in color. Copies of this patent with color drawings will be provided by the Office upon request and payment of the necessary fee.

FIG. 1 is a color perspective view from front, left, top-side of a current transducer showing our new design;

FIG. 2 is a color view from the right side thereof;

FIG. 3 is a color view from the rear side thereof;

FIG. 4 is a color view from the front side thereof;

FIG. 5 is a color view from the left side thereof;

FIG. 6 is a color bottom plan view thereof; and,

FIG. 7 is a color top plan view thereof.
